DESIGN FOR A BADGE OR SIMILAR ARTICLE

Roman Van Den Borre, Mishawaka, Ind.

Application March 18, 1942, Serial No. 106,226

Term of patent 14 years

To all whom it may concern:

Be it known that I, Roman Van Den Borre, a citizen of the United States of America, residing at Mishawaka, county of St. Joseph and State of Indiana, have invented a new, original, and ornamental Design for a Badge or Similar Article, of which the following is a specification, reference being had to the accompanying drawing, forming a part thereof wherein:

The essential feature of the design resides in the portion shown in full lines. While I have disclosed the design in the form of a badge or similar article, it is understood that the same may be embodied in other similar articles without departing from the spirit of the invention.

I claim:

The ornamental design for a badge or similar article, as shown and described.

ROMAN VAN DEN BORRE.
